UNITED STATES PATENT OFFICE.

JAMES H. BYRNES, OF FLUSHING, NEW YORK.

METAL WINDOW.

Application filed July 8, 1922, Serial No. 573,541. Renewed December 7, 1927.

This invention relates to windows and sliding frames generally and preferably of the wholly metal types.

An object of this invention is to provide a construction of windows and the like whereby the frame of the window may be assembled prior to shipment to the location of installation and thereby obviate the need of adjustment of the parts of the window frame relative to one another during the stage of installation.

Such provision of wholly closed or imperforate jamb, head and sill construction precludes access of the weather interiorly of the window frame and prevents deterioration and also affords less costly treatment for preservation.

A further object of the invention is to provide a rigid frame for windows and the like whereby a race is provided for the upper and lower sashes respectively and combined with the window frame to safeguard against entry of rain, wind and the like within the interior of the building.

A further object of the invention is the provision of a multiple point sliding contact arrangement coacting with a guide race for insuring anti-rattling, ease of operation and sealing against the weather.

A further object of the invention is to provide a construction of window comprising a frame of rigid material to locate the weight chains out of sight and preferably in alignment with the path of travel of the sash, thereby also deriving decreased width of the jambs.

A further feature of the invention is to provide a construction for windows and frame therefor of metal or like rigid material whereby the frame may be installed as a unit within the window opening in the building, to afford positioning of the upper and lower window sash thereafter and to enable the setting of the glass in the upper and lower window sashes at a still later stage.

With the above named objects in view and other objects, a preferred form of the invention comprises a window frame composed of the oppositely disposed jambs, a head-rail and a sill, each jamb being of hollow frame construction and provided with a frontal plate having longitudinally extending de-

pressions, guide races of hollow steel constructed to be respectively positioned in such longitudinally extending depressions and set 55 by means of set screws or the like, such guide races being each wholly imperforate excepting for the slot through which is received a two-point sliding contact member secured to the upper and lower sash respectively and forming a part thereof, the contacts of which engage inner surfaces of the guide race at opposed locations; such head-rail being of hollow construction and provided with a slot having converging and diverging surfaces 65 combined with a self-adjusting closure channel to afford automatic sealing against wind and rain and provide anti-rattling and preclude sagging and distortion; the sill of such frame being provided with a self-cleaning 70 angle plate for sealing the lower edge of the lower sash when in closed position; and the lower edge of the upper sash and the upper edge of the lower sash being provided with coacting meeting rails to afford contact at 75 non-aligned areas when the sash are both in closed position, to provide for anti-rattling and further for sealing against wind and rain and sagging and distortion.

Further features and objects of the invention will be more fully understood from the following description and the accompanying drawings, in which

Fig. 1 is an elevation of a window embodying my invention as viewed from the 85 interior of the building of installation;

Fig. 2 is an elevation of the same as viewed from the exterior of the building;

Fig. 3 is a detail interior elevation of the head frame, the upper sash and the lower 90 edge portion of the upper sash;

Fig. 4 is an interior elevation of the sill and lower edge portion of the lower sash and also illustrating a form of bracket co-operating with the sill plate for supporting 95 a radiator;

Fig. 5 is a vertical central sectional view taken on line 5—5 of Fig. 1 intermediately broken away, of the window shown in Figs. 1 and 2;

Fig. 6 is a horizontal sectional view taken on line 6—6 of Fig. 1;

Fig. 7 is a detail horizontal sectional view of the front plate of a jamb and of the two

races for the upper and lower window respectively and showing the weight opening plate;

Fig. 8 is a detail vertical section showing 5 the weight pulley and chain;

Fig. 9 is a detail side elevation of the bracket for supporting the radiator or the like from the interior over-hanging edge of the sill;

10 Fig. 10 is a detail sectional view on line 10—10 of Fig. 9; and

15 Fig. 11 is a detail vertical sectional view on an enlarged scale of the meeting rails of the lower and upper sash, showing the non-aligned, opposite surfaces of contact.

20 The left-hand jamb of the window is indicated at 11 and the right-hand jamb at 12, the head of the window is shown at 13 and the sill is indicated generally at 14.

25 The upper window sash is denoted 15 and the lower window sash is denoted 16.

30 The jambs 11, 12 are usually similar in construction and preferably comprise a casting having a rearward wall 18, and lateral wall 19 disposed interiorly of the building of installation and preferably extending rectilinearly from the face 20 of the wall of the building. It will be understood that the exposed portion of the wall 19 may be 35 curved or of other configuration as may be desired for the purposes of ornamentation, the preference as to rectilinear extension of the wall 19 being stated from the viewpoint of attainment of minimum width of the jamb. The jamb further comprises the wall 21 disposed exteriorly of the building of installation, which wall 21 is preferably bent outwardly as is indicated at 22. The rear wall 18 and the interior wall 19 and the 40 exterior wall 21 are preferably integral or unitary in construction and provided with a suitable form of flange 23, or the like extending exteriorly of the casing 17 serving as an anchor in the cement, concrete or the like. Such flange 23 is shown in the 45 form of double thickness, thereby facilitating the union of the rear wall 18 and outward wall 21 by welding, riveting or the like. Each jamb further comprises the frontal 50 plate 24 having the off-set outward end portion 25, for connection with the end portion of the outwardly bent portion 22 of the wall 21 by means of welding, screws, or by rivets, or the like. The frontal member 24 55 further comprises the inward end portion 26 for connection with the end portion of the inward wall 19 by welding, or by means of rivets, screws or the like.

60 Intermediately located on the exterior of the frontal member 24 are provided the vertically extending depressions 27, 28 respectively in alignment with the paths of travel of the upper sash 15 and the lower sash 16, and in which depressions are removably located the opposite guide races 29 for the

upper sash 15 and the opposite guide races 30 for the lower sash 16. The races 29 and 30 are usually of similar construction and a specific description of the one will suffice for the other.

70 Taking the race 30 for the lower sash 16, the same is of hollow construction and formed of steel or other suitable metal or other rigid material and shaped to be substantially wholly closed or imperforate, see 75 Figs. 7 and 6, excepting the frontal wall member 31 being provided with the longitudinally, i. e., vertically extending slot 32 through which is received the flange of the two-point sliding contact 33 of the lower 80 sash 16.

85 Preferably the two-point sliding contact 33 of the lower sash 16 is formed of the exteriorly disposed, inwardly off-set flange 35 extending through the slot 32 and having at its free end an outwardly directed edge portion 36, the two-point sliding contact 33 further comprising the strip 37 disposed inwardly of the sash 16 and jointly with the flange 35 extends through the slot 32 and is 90 provided at its free end with the interiorly directed edge portion 38.

95 By such provision of means the two divergently directed contact members 36, 38 extend into engagement or in close adjacency to the inner faces of oppositely disposed interior walls of the race 30. The 100 terminal portions of such contact members 36, 38 may be rounded as is indicated in Fig. 6, to facilitate installation and assembly. The flange 35 is preferably integral with the frame 39 which extends integrally both at the top and bottom as well as the two opposite lateral sides of the sash and is 105 preferably located on the outward face of the sash.

110 The strip 37 is removably secured to the flange 35 by means of setting screws, bolts, or like removable means, the advantages of which will be more fully apparent as set forth hereinafter.

115 The guide flange means 34 of the upper sash 15 is similar to the guide flange means 33 of the lower sash and the individual elements are indicated by the same reference numbers.

120 The races 29, 30 are respectively positioned within the depressions 28, 27 by means of the setting screws 40 or the like.

125 Internally of each jamb is also provided a separator or spacing wall 41 located intermediate of the path of travel of the weight 42 for the lower sash 16 and the weight 43 for the upper sash 15, see Fig. 6.

130 The head 13 is preferably of hollow construction of steel or other metal of other rigid material, and is composed of an inwardly exposed wall 45, the concealed upper wall 46, the concealed outward wall portion 47, the exposed outward wall portion 48 and

the lower wall member 49. At a suitable location on the lower wall member 49 is provided a self-sealing means 50 having a slot 51 for receiving the upper edge flange 52 of the frame 53 of the upper sash 15. Such slot is preferably formed with walls 54, 55 converging at their portions thereof adjacent the exposed opening of the slot 51 to a certain region, where the walls 54, 55 extend divergently as is indicated at 56, 57 respectively. Such region is adjacent to the extreme upper edge of the flange 52 of the upper sash 15 when the sash 15 is in its fully closed or uppermost position, whereby effectual contact is made by the walls 54, 55 respectively on opposite sides of the upper strip 52 of the upper sash 15.

Located above the terminal portions 56, 57 and extending on each side about such terminal portions 56, 57 is provided the closure channel 58 having the lateral converging flanges 59, 60, coacting with the respective converging wall portions 54, 55, and diverging wall portions 56, 57 aforesaid, whereby a sealing closure is effected about the inward opening of the slot 51 by pressure contact of the lateral converging flanges 59, 60 with the walls 54, 55. The channel 58 is disposed freely relatively to the flanges 54—56 and 55—57 whereby upon lowering of the upper sash 15, the flanges 59, 60 of the channel 58 are freed and upon re-raising of the upper sash 15 the channel automatically adjusts its closing and sealing action with the slot flanges 54—56, 55—57 conforming to wear or possible bending of the engaged parts.

At the lower edge of the upper sash 15 is provided the vertically extending flange 62, preferably integral with the horizontally extending flange 63, projecting inwardly relative to the window opening to a certain region and thence extending angularly upwardly as indicated at 64, see also Fig. 11. On the inward horizontal lower edge of the upper sash 15 is provided suitable securing means for the glass of the upper sash 15, such securing means being preferably a narrow channel member 65 removably secured to the flange 63 by means of the set screw 66. The exposed inwardly disposed face 67 of the channel member 65 is located in spaced relation with the aforesaid angular upwardly directed flange 64, and such members 64—67 serve as a meeting rail for the lower edge of an upper sash 15.

The upper edge of the lower sash 16 is provided with a coacting meeting rail, preferably also integral with the frame member 60 for securing the glass of the lower sash 16 and comprising the inwardly disposed, exposed flange 68 secured, preferably integrally, to the horizontally extending flange 69 carrying the outwardly disposed, angularly downwardly extending flange 70. The up-

per, outward edge of the lower sash 16 comprises the flange 71 to which is secured the outwardly projecting free flange 72, extending curvedly downwardly. The flange member 68—69—70 as a unit is removably secured to the flange member 71—72 by means of the screws 73. Upon raising the upper sash 15 to its uppermost position and lowering the lower sash to its lowermost position contact is effected on the inward face 75 of the flange 64 with the outward face of the curvedly, downwardly extending flange 72 at the region indicated in Fig. 11 and by the reference character 73 and contact is effected on the outward face of the flange 64 80 and the inward face of the angularly, downwardly extending free flange 70 at the region indicated by the reference character 74. By such provision of means, the region 73 is disposed out of horizontal alignment with 85 the region 74 and by reason of the divergence to the vertical of the respective downwardly extending free flanges 70, 72 and the angularly upwardly extending flange 64, contact at such non-horizontally aligned regions 73, 74 is maintained notwithstanding wear of the engaging parts and possible bending, incident to repeated use.

The lower frame of the lower sash 16 comprises the flange 75 preferably integral with 95 the lateral flanges 76, 77, of the lower sash 16, which latter in turn, as above stated, are integral with the upper flange 71. The lower flange 75 is bent at 78 about the lower horizontal edge of the glass of the lower sash 100 16 and thence extends substantially vertically downwardly at 79.

On the inward face of the lower sash 16 is provided the flange 80 removably secured by the screws 81 to the aforesaid downward flange 79.

At the lower terminal portion of the flange 80 is provided the angular flange member 82 coacting with the retaining angular plate 83 of the sill 14, such retaining plate 83 comprising the intermediate portion 84 extending at an angle convergently relative to the angular flange member 82 of the lower flange 81. The extreme edge portion 85 of the angular flange 82 is preferably normally 110 spaced from the inward face of the aforesaid flange 79, at the lower edge of the lower sash 16, to enhance the resiliency of the angular flange portion 82 and it will be noted that the retaining member 83 is secured at its upper edge 86 to the inward plate 87 of the sill 14 and at its lower edge 88 to the outward, downward sloping plate 89 of the sill 14, whereby the intermediate portion 84 is provided with rigid and as 120 well with a restricted extent of resiliency, in coaction with the sill and flange 82 of the lower sash 16.

The lower strip 79 of the lower sash 16 coacts with the vertically inclined interme- 130

diate inclined portion 99 of the sill retaining plate 83, thereby affording sliding, converging contact between the lower strip 79 and the intermediate inclined portion 99, 5 similar to the sliding converging contact between the angular flange portion 82 and the intermediate inclined portion 84.

It will also be noted that the retaining plate 83 is of such configuration to avoid 10 any closed pocket or the like whereby dust, rain and the like are prevented from accumulation and upon opening of the window are exposed to the wind for self-cleansing and drainage.

15 The inward apron 90 of the sill 14 is preferably curved interiorly as is indicated at 91 and spaced from the wall 92 to provide a clearance for the reception of an angular bracket 93 for supporting a radiator 94, as is 20 indicated in Figs. 1, 4, 5, 9 and 10. Such bracket 93 may include the spaced supporting arms 95, 96, see Figs. 1 and 4 respectively secured by screws 97 to the vertically extending plate 98 of the bracket 93. It will 25 be noted that the arms 95, 96 of the brackets 93 engage the radiator between the inner radiator sections; such arrangement permits the radiator 94 to be securely hung without marring the wall and also to permit adjustment of the radiator horizontally relatively to the sill 14 by merely shifting the bracket 93 horizontally in the groove formed by the upturned angular edge 92 at the apron 90.

30 35 Preferably in such preferred forms of the invention, the window frame composed of the opposite jambs 11, 12, the head 13 and the sill 14 are connected as a unit at the place of manufacture by welding, riveting or 40 the like to one another, preparatory to shipment to any location of installation. The window frame is positioned within the mason's daylight opening in the building by mere placement against the masonry and 45 held in place by brick, tile or lugs or other suitable means on the interior.

If desired, the cap lintel 100 may be of 50 stone or may be of brick and may be finished by means of an angle plate 101. The sill lintel 102 may be of stone, brick, or other suitable material.

55 As is indicated in Fig. 5, upon placing the window frame within the mason's daylight opening, the head 13, and likewise the inward faces of the jambs 11, 12 may be covered by plaster indicated generally at 103, which may be extended on the inward faces of the head and jambs to such extent as may be desired. On the outward face 48 of 60 the head 13, the clearance between the head 13 and the cap lintel 100 may be sealed by cementing 104.

65 The sill 14 is positioned on the lower horizontal masonry 105, see Fig. 5, of the mason's daylight opening, by means of concrete 106

or other cement, the angle plate 107 of structural steel or the like or otherwise as may be preferred. In Fig. 6, the inward facing material is indicated at 108 of laths or other material and an exterior finishing layer 109 70 of plaster.

The window proper may be assembled in the window frame at a later period, if desired. The installing of the window sash is effected by removing the weight opening plate 110 (see Fig. 5) in each jamb, placing the weights 42, 43 in the respective compartments 112 and 113 of each jamb, passing a weight chain 114 (see Fig. 8) over the respective pulleys 115 and feeding the same 80 downwardly. The sash weights are then respectively connected to the weight chains 114 by means of the usual connectors and a nail or the like is passed through a link in the chains 114 to hold the weight at a proper height. Whereafter the weight opening plates 110 are replaced.

85 The outer pair of chains 114 are then secured to the upper sash 15, as will be understood and the upper sash raised to its uppermost position. The inner pair of chains are then similarly secured to the lower sash 16 and the lower sash raised to its uppermost position.

90 95 The opposite pairs of races 29, 30 are then passed over the respective oppositely extending two-point sliding contact members 34, 33 of the respective upper and lower window sash 15, 16 and within the respective depressions 27, 28 of the frontal plates 24, and moved to the upper ends of the respective depressions 27, 28, and the races 29, 30 are 100 respectively set in position by means of the set screws 40.

105 It will be noted that the races 29, 30 are imperforate, i. e., wholly closed to the atmosphere excepting through its slot 32 on their exposed or frontal faces and wholly imperforate on the concealed faces thereof excepting at the opening 120, see Fig. 8, receiving 110 the outward circular portion of the pulley 115, rotatably mounted in a suitable bracket 121 secured at the upper portion of the frontal plate 24. The front leads of the weight chains 114 are respectively secured 115 to the guide flanges 34, 33 of the upper and lower sash 15, 16 respectively as by attaching the outer ends of the respective chains 114 through suitable openings in the guide flanges 33, 34 of the respective sash 15, 16, or by any other suitable arrangement.

120 125 After positioning the window frame in the mason's daylight opening and the assembling of the upper and lower sash with their respective races, weights and weight chains, the glass of the sash may be positioned at a final stage. The glass of the upper sash is positioned by removing the inward top flange 125, see Figs. 1 and 5 by loosening the setting screws 126, also loosen-

ing one removable lateral flange 127 then sliding the glass in the frame of the upper sash 15 puttying or cementing or the like, and replacing the aforesaid removable flanges 125, 127.

The glass of the lower sash 16 may be positioned by removing the uppermost flange 68, 69, 70 by unscrewing the setting screw 73 then passing the glass through the slot formed between the outward and inward side flanges of the lower sash, puttying, cementing or the like and then replacing the uppermost strip 68—69—70.

A horizontally extending strip 135 is located substantially centrally between the races 29, 30 to be engaged respectively with the upper edge flange of the lower sash 16 and the lower edge flange of the upper sash 15, to seal leakage of air, wind and rain between the races when the upper and lower window sash are closed.

Whereas I have described my invention by reference to specific forms thereof it will be understood that many changes and modifications may be made without departing from the spirit of the invention.

I claim:

1. In a metal window, the combination of oppositely disposed jambs, each of hollow metal construction, the exposed faces of which are provided with longitudinally extending depressions, hollow races for the respective upper and lower window sash, said races having frontal faces disposed respectively adjacent the lateral faces of the sash, said frontal faces being provided with slots and means accessible through said slots for removably positioning said races respectively in said depressions.

2. In a metal window, the combination of oppositely disposed jambs having exposed frontal faces provided with spaced longitudinally extending depressions, imperforate hollow races disposed in said depressions, said hollow races being provided with frontal slots, means accessible through said frontal slots for removably positioning said hollow races and guide plates carried by the upper and lower sash and projecting respectively in said slots.

3. In a metal window, the combination with opposite jambs, each jamb having imperforate outward and inward walls and further having a frontal plate provided with spaced vertically extending depressions, races disposed in said depressions, said races being provided with frontal slots, means accessible through said frontal slots for removably positioning said races, guide members respectively carried by the upper and lower sash and projecting in said slots, weights disposed in said jambs, and weight chains for said weights respectively and respectively connected to said guide flanges.

4. In a metal window, the combination

with the frame of the upper sash, of a head member of the window frame provided with a slot, a flange secured to the upper edge of said upper sash and arranged to enter said slot when the upper sash is in its uppermost position and a channel member disposed inferiorly of said head for sealing the inner opening of said slot.

5. In a metal window, the combination with the frame of the upper sash, of a head member of the window frame having a slot formed of anteriorly disposed converging faces, a flange secured to the upper edge of said upper sash and arranged to enter said slot when the upper sash is in its uppermost position and a channel member inferiorly of said head for sealing the inner opening of said slot.

6. In a metal window, the combination with the frame of the upper sash, of a head member of the window frame having a slot formed of anterior converging faces and posterior diverging faces, a flange secured to the upper edge of said upper sash and arranged to enter said slot when the upper sash is in its uppermost position and a channel member disposed inferiorly of said head for sealing the inner opening of said slot.

7. In a window, the combination with a sill, of a double angular plate carried by said sill and having two predetermined faces thereof extending at different angles to the vertical, a lower sash, spaced sealing flanges carried at the lower edge of said lower sash and arranged to contact with said predetermined faces of said angle plate when the lowermost sash is in its lowermost position.

8. The combination of a jamb having imperforate exposed faces and a frontal face provided with a depression, a race disposed in said depression and having imperforate exposed faces and a frontal slot, a sash, a lateral flange carried by said sash and a guide member carried by said flange and guiding said sash by contact with opposite faces of said race interiorly of said slot.

9. The combination of a jamb having imperforate exposed faces and a frontal face provided with a depression, a race disposed in said depression and having imperforate exposed faces and a frontal slot, a sash, a lateral flange carried by said sash, means for removably positioning said race in said depression, and a guide member carried by said flange and guiding said sash by contact with opposite faces of said race interiorly of said slot.

10. The combination of a jamb having imperforate exposed faces and a frontal face provided with spaced depressions, a race disposed in each depression, each race having imperforate exposed faces and a frontal slot, means accessible through said frontal slot for removably positioning said race, a sash, a lateral flange carried by said sash and a

guide member carried by said flange and guiding said sash by contact with a face of said race interiorly of said slot.

11. The combination of a jamb having imperforate exposed faces and a frontal face provided with a depression, a race disposed in said depression and having imperforate exposed faces and a frontal slot, means accessible through said frontal slot for removably positioning said race, in said depression, a sash, a lateral flange carried by said sash, and divergent flanges carried by said lateral flange and engaging opposite interior faces of said race.
12. The combination of a jamb having imperforate exposed faces and a frontal face provided with spaced depressions, a race disposed in each depression and having imperforate exposed faces and a frontal slot, means accessible through said frontal slot for

removably positioning said race, a sash, a lateral flange carried by said sash and two divergent flanges carried by said lateral flange and engaging opposite faces of the interior of its race.

25

13. The combination of a jamb having imperforate exposed faces and a frontal face provided with a depression, a race disposed in said depression and having imperforate exposed faces and a frontal slot, a sash, a lateral flange carried by said sash, means for removably positioning said race in said depression, and a guide member carried by said flange and two divergent flanges carried by said lateral flange and engaging opposite faces of the interior of its race.

30

35

In testimony whereof I have signed this specification this 13th day of June, 1922.

JAMES H. BYRNES.
